TELEPHONE SYSTEM

Owen Avis Pearce, Heswall, Wirral, and Sidney Hugh Oliver, Ainsdale, Southport, near Liverpool, England, assignors, by mesne assignments, to Automatic Electric Laboratories, Inc., Chicago, Ill., a corporation of Delaware

Application October 15, 1942, Serial No. 462,082

In Great Britain December 18, 1941

11 Claims. (Cl. 179—18)

The present invention relates to telephone systems and is more particularly concerned with private automatic branch exchange systems of the type provided with facilities for enabling local subscribers to gain access to a main exchange line by dialling a special digit or exerting some other special control. The invention moreover relates to systems of this type having local connections completed over local finder-connector links while main exchange connections, both incoming and outgoing, are completed over exchange finders having their banks multiplied to those of the local finders. Such a layout lends itself readily to the provision of arrangements whereby any one of a number of subscribers may answer incoming main exchange calls and also whereby main exchange calls may be transferred from one party to another. The main object of the invention is to provide improved and simplified arrangements for controlling the setting of the exchange finder switches.

According to one feature of the invention, in a private branch exchange telephone system having local calls set up over finder connector links and having main exchange calls completed without the help of an operator over finder switches individual to the exchange lines, a circuit for starting up an exchange finder switch is adapted to be completed to a subscriber's line circuit over either of two positions in the connector bank, one of which corresponds to his line while the other is characteristic of outgoing main exchange service.

According to another feature of the invention, in a private branch exchange telephone system having local calls set up over finder connector links and having main exchange calls completed over finder switches individual to the exchange lines, the marking of a subscriber's line in the banks of finders of the two types is selectively effected over the same contact of the subscriber's line relay.

A further feature of the invention is that in a private branch exchange telephone system having local calls set up over finder connector links and having main exchange calls completed without the help of an operator over finder switches individual to the exchange lines, the operation of a subscriber's line relay is adapted to cause a local finder switch to connect with the line whereupon the subscriber's cut-off relay is operated and the line relay is released, the operation of the line relay while the cut-off relay is operated serving to cause an exchange finder to associate itself with the subscriber's line.

The invention will be better understood from the following description of one method of carrying it into effect, reference being had to the accompanying drawing in which the invention is assumed to be applied to a private automatic branch exchange, hereinafter abbreviated P. A. B. X, provided with the above-mentioned facilities and of the general type disclosed in British specification No. 389,867.

The drawing shows the circuits of a subscriber's line equipment LE, together with such parts of the circuits of a local link LL and its associated line finder switch LFS and connector switch CS and of an exchange link EL together with its associated finder switch EFS, as is necessary for understanding the underlying principle of the invention. The P. A. B. X is assumed to be of the single digit type having a capacity for nine local subscribers requiring the digits 1—9 while the digit 0 serves for main exchange service. The rotary switches LFS, CS and EFS are all assumed to be of the 11-point self-interrupted drive step-by-step type moving always in the same direction. The finder switches LFS and EFS have no normal position but the connector switch CS which responds to impulses is restored to normal after use under the control of an off-normal bank (not shown).

Considering now the detailed operation, when 30 a local P. A. B. X subscriber removes his receiver to originate a call, the incoming negative and positive conductors on the left of the drawing are looped and the line relay R operates. Thereupon at contacts *r1* the cut-off relay K is disconnected from the incoming P lead to mark the line as 35 busy to the link connector switches, at contacts *r2* marking battery via resistance YA is extended over resting contacts *k4* to bank LFS5 of the local link finder switches, and at contacts *r3* earth is 40 extended over resting contacts *k5* via suitable allotting equipment 10 to operate the start relay ST in the local link shown which is assumed to be the one allotted for use. Thereupon at contacts *st1* earth is applied to lead 11 to complete 45 a driving circuit for the magnet of the line finder switch LFS and at contacts *st2* a circuit is prepared for the test relay T. When the finder switch wipers reach the calling line, the test relay T operates in series with resistance YA and 50 provides an immediate guard on the outlet seized by virtue of its low resistance. At contacts *t1* the finder magnet driving circuit is opened and an operating circuit is completed for the low resistance switching relay HA in series with the calling 55 subscriber's cut-off relay K. Relay HA thereupon

at its contacts *ha1* and *ha2* extends the calling line through to the local link *LL*, whereupon relays *A* and *B* operate and a holding circuit is completed for relay *HA* over contacts *b2* and *ha3*. Relay *K* at contacts *k1* and *k2* disconnects the line relay *R* from across the line and also at contacts *k1* connects it to lead *J* in readiness for further operation if required. At contacts *k3* relay *K* is connected to the incoming *P* lead which however remains busied by virtue of the low resistance earth through the winding of relay *HA*. At contacts *k4* and *k5* the marking and start circuits of the local link are opened, further points in these circuits being opened at *r2* and *r3* on the release of relay *R*.

If a local extension subscriber is required, the subscriber dials one of the digits 1-9. Relay *A* responds and at its contacts *a1* transmits impulses over lead *l2* extending to the connector switch driving magnet, whereupon the wipers *CS1*-*CS5* are advanced to the required position. Connection is effected over the connector switch multiple *CSM* to the required local party in known manner on the operation of the switching relay *H* in series with the called subscriber's *K* relay.

If the calling subscriber requires to effect a main exchange connection, the digit 0 will be dialled in response to which the wipers of switch *CS* will be advanced to the last position 11. Earth is thereupon extended over wiper and bank *CS5*, wiper and bank *LFS4* and lead *J* to re-operate the calling party's line relay *R*. With both relays *R* and *K* operated the marking battery potential is transferred to bank *EFS1* of the exchange finder switch *EFS*, while the start earth potential is extended to the exchange finder start lead *l3*. The exchange finder switch *EFS* now rotates in search of the calling line marking, and when it reaches the required position the test relay *TT* operates. This brings up a switching relay (not shown) which serves to connect the calling line through to the battery feeding and impulsing relay *AA*, and also connects direct earth over wiper and bank *EFS4* to hold relay *K* and at the same time to short-circuit relay *HA*. Relay *HA* thereupon releases and opens the circuit of relay *A* which in turn releases relay *B* whereupon the connector switch is restored to its home position and the local link is freed for further common use. The calling line is now connected by way of the exchange finder switch banks and wipers and the exchange link *EL* to the main exchange junction line *MEJ*.

The same marking principle may also be employed to control the operation of an exchange finder under call transfer conditions. If a local subscriber who has been in connection with a main exchange subscriber over an exchange finder switch and an associated exchange link desires to communicate with a local party with the probable intention of transferring the call, he will operate a push button provided on his telephone which in the manner described in British specification No. 389,867 sends a signal to the exchange link and causes the main exchange connection to be held, while access is had to transfer equipment (not shown). This takes into use a local link such as *LL* over the wipers and banks of the associated finder switch and the local party then dials the number of the party to whom the call is to be transferred. If the called local party desires the call to be transferred to him, the calling local party hangs up, whereupon releasing relays *A* and *B*. Since a

so-called transfer relay *TR*, not shown but assumed to be provided in the local link, will have been operated in this instance, on the release of relay *B* earth is connected over contacts *b1* and contacts *tr* of relay *TR* and wiper and bank *CS4* and then over the *J* lead to operate the *R* relay of the called local party in addition to his *K* relay which will have been operated already in series with the *H* relay of the calling local link. The operation of relays *R* and *K* together causes a start signal to be extended to the appropriate exchange finder switch if more than one is provided, in substantially the manner already described and a marking corresponding to the called local line is also applied to the bank of the exchange finder switch. The wipers of this switch accordingly rotate to connect with the called local line after which it will effect the full release of the local link taken into use and also the transfer equipment. The called local party is now left connected through to the main exchange subscriber over switch *EFS* and exchange link *EL*.

As regards incoming calls, these can be handled in several ways but no specific details are shown. One possibility is to provide an additional testing bank on the exchange finder to which marking potential is applied directly by contacts such as *r2*. An incoming call would then effect the ringing of a common bell and would change over relay *TT* to the auxiliary testing bank while further contacts between contacts such as *k5* and the allotting equipment *l0* would ensure the start circuit being extended to the required exchange finder. Hence when a party hearing the ringing of the common bell removed his receiver, the operation of relay *R* would start up the finder associated with the main exchange line in question and mark the appropriate contact in the auxiliary bank so that the answering party would be connected through.

An alternative arrangement would be to arrange that the relay which responded to the incoming call applied earth to the wiper such as *LFS4* of the next idle local finder. Thus when a party removed his receiver to answer the incoming call, this finder would connect with his line and relay *R* would then be re-operated. Consequently earth would be connected to lead *l3* and extended to the start circuit of the appropriate finder, which on connecting with the answering party would release the local link by short-circuiting relay *HA* as previously described.

It will thus be seen that the line equipment *LE* is marked on differing finder banks according as to whether the line relay *R* is operated alone or in addition to the cut-off relay *K* and by this means the local line marking arrangements for use in connection with exchange finder switches are greatly simplified in comparison with the arrangements hitherto proposed.

The method of line marking according to the invention finds particular advantage in cases of larger capacity P. A. B. X's where it may be necessary to utilise switches of the two-motion type which require separate markings for the two directions of motion when used as finders. Such arrangements are shown in essence in British Patent No. 554,137, issued Sept. 16, 1943, where a line relay circuit incorporating the present invention is applied in connection with improved night service facilities on operator-attended P. A. B. X boards.

What we claim as new and desire to secure by Letters Patent is:

1. In a telephone system, an exchange, subscribers' lines terminating at the exchange, a trunk line outgoing from said exchange to another exchange, automatic switching equipment at said first exchange over which local calls between said subscribers' lines are completed, said equipment including a connector switch having a different position for each called subscriber's line and having a special position characteristic of said trunk line, apparatus individual to each subscriber's line at times operated over said connector switch while same occupies the position corresponding to that subscriber's line and at other times operated over said switch while same occupies the position characteristic of said trunk line, and a finder switch at said first exchange terminating said trunk line and effective responsive to the operation of said apparatus individual to any subscriber's line to search for that subscriber's line.

2. In a telephone system, subscribers' lines, a trunk line, a connector switch, wipers on said switch having different positions corresponding respectively to the different ones of said lines, means for seizing said switch and operating its wipers to a position corresponding to any of said lines, a finder switch terminating said trunk line and having access to all of said subscribers' lines, a circuit individual to each one of said subscribers' lines for starting said finder switch to hunt for that one of said subscribers' lines, means for at times completing said start circuit over a wiper of said connector switch while same occupies a position corresponding to said one subscriber's line and means for at other times completing said start circuit over a wiper of said connector switch while same occupies a position corresponding to said trunk line.

3. In a telephone system, subscribers' lines, a trunk line, a connector switch, wipers on said switch having different positions corresponding respectively to the different ones of said lines, a finder switch effective responsive to the initiation of a call by any of said subscribers' lines to search for and seize that line, a connection thereafter extended from the calling line over said finder switch to said connector switch, means for operating said connector switch directly over said connection thereby to move its wipers to a position corresponding to said trunk line or to any desired one of said subscribers' lines, a finder switch terminating said trunk line and having access to all of said subscribers' lines, a circuit individual to each one of said subscribers' lines for starting said last finder switch to hunt for that one of said subscribers' lines, means for at times completing said start circuit over a wiper of said connector switch while same occupies a position corresponding to said one line, and means for at other times completing said start circuit over a wiper of said first finder switch and a wiper of said connector switch in series while said connector switch occupies a position corresponding to said trunk line.

4. In a telephone system, a plurality of subscribers' lines each having a line relay and a cut off relay, means for operating any of said line relays over its associated line, a finder switch having access to all of said lines and effective upon operation of said line relay to search for the line associated with said relay, means responsive to said switch finding said line for operating the cut off relay associated therewith, thereby to restore said line relay to normal, an alternative circuit for said line relay prepared by

5 said cut off relay upon its operation, switching apparatus controlled over said line and said finder switch in series thereby at times to extend a connection to another one of said subscribers' lines and thereby at other times to reoperate said line relay over said alternative circuit, a trunk line, a finder switch terminating said trunk line and having access to all of said subscribers' lines, said last finder switch effective upon said reoperation of said line relay over said alternative circuit to search for the subscriber's line associated with that line relay and connect said trunk to said subscriber's line.

15 6. In a telephone system, a plurality of subscribers' lines each having a line relay and a cut off relay, means for operating any of said line relays over its associated line, a finder switch having access to all of said lines and effective upon operation of said relay to search for the line associated with said relay, means responsive to said switch finding said line for operating the cut off relay associated therewith, thereby to restore said line relay to normal, an alternative circuit for said line relay prepared by said cut off relay upon its operation, means for at times reoperating said line relay over said alternative circuit, and a second finder switch having access to all of said lines effective upon such reoperation of said line relay to search for the line associated therewith.

20 7. In a telephone system, a plurality of subscribers' lines each having a line relay and a cut off relay, means for operating any of said line relays over its associated line, a finder switch having access to said lines and effective responsive to such operation of a line relay to search for and seize the line associated with that relay, means for at times operating any cut off relay thereby to prevent its associated line relay from being operated over the associated line, an alternative circuit for said line relay prepared by said cut off relay upon its operation, means for operating said line relay over said alternative circuit, and a second finder switch having access to all of said lines and effective responsive to such operation of said line relay over said alternative circuit to search for the line associated with that line relay.

25 8. In a telephone system, a plurality of subscribers' lines, two finder switches each having access to all of said lines, a line relay and a cut off relay for each of said lines, means for at times operating both of the relays associated with a particular line concurrently and for at other times operating each of the relays associated with that line alone, means controlled by said relays for causing one of said switches to search for said particular line whenever a particular one of the relays associated with that line is operated alone and for causing the other of said switches to search for said particular line whenever both of the relays associated with that line are operated concurrently.

30 9. In a telephone system, a plurality of subscribers' lines, two finder switches each having access to all of said lines, a line relay and a cut off relay for each of said lines, each said line having a circuit extending over a make contact on its associated cut off relay for causing one of said switches to start hunting for that line and a circuit extending over a break contact on its associated cut off relay for causing the other one of said switches to start hunting for that line, both of said circuits for any particular one

of said lines including the same contact on the line relay for that line.

9. In a telephone system wherein each of a plurality of subscribers' lines is connected in multiple to the banks of two finder switches, and wherein each of said switches at times is operated to hunt for a marked subscriber's line, a line relay and a cut off relay individual to each subscriber's line, each line also having a circuit extending over a front contact of that line's cut off relay for at times marking said line in the bank of one of said switches and another circuit extending over a back contact of that line's cut off relay for at times marking said line in the bank of the other of said switches, and both of the marking circuits for each line including the same contact on the line relay for that line.

10. In a telephone system, a subscriber's line, a line relay normally connected to said line, means for at times operating said relay over said line, a cut off relay operated at other times to disconnect said line relay from said line, a contact on said cut off relay effective at such other times to prepare an alternative circuit for said line relay, means for operating said line relay over said alternative circuit, and a switch

effective responsive to the operation of said line relay over said alternative circuit but not responsive to the operation of said line relay over said line for extending a connection to said line.

11. In a telephone system, a subscriber's line, a line relay normally connected to said line and operable thereover, a cut off relay associated with said line, a numerical switch in whose bank appear a plurality of lines including said subscriber's line, means for seizing said switch and operating it to any line of said plurality, means in said switch for operating said cut off relay when said switch is operated to said subscriber's line thereby to disconnect said line relay from said subscriber's line, a contact on said cut off relay thereupon effective to prepare an alternative circuit for said line relay, means for at times completing said alternative circuit over said switch thereby to operate said line relay, and another switch effective responsive to the operation of said line relay over said alternative circuit but not responsive to an operation of said line relay over said subscriber's line for extending a connection to said line.
